UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

CONSTRUCTION FOR DOUGH-BOARDS AND SIMILAR ARTICLES.

1,233,184.

Specification of Letters Patent. Patented July 10, 1917.

Application filed April 17, 1914. Serial No. 832,438.

To all whom it may concern:

Be it known that I, LEE S. CHADWICK, a citizen of the United States, residing at East Cleveland, in the county of Cuyahoga and State of Ohio, have invented a certain new and useful Improvement in Construction for Dough-Boards and Similar Articles, of which the following is a full, clear, and exact description, reference being had to the accompanying drawings.

This invention relates to a built-up slab or board, that is especially suitable for use as a dough-board, table top or other similar articles; and it has for its objects to provide a slab or board of this kind which comprises a heavily enameled metal shell and a wooden filler; which possesses a very firm, non-yielding working surface or portion; which may be very easily kept clean; which is of neat and attractive appearance; and which is constructed with the object in view of protecting the enamel of the shell against fracture during both the assembling of the board and its use; and in which the filler and the shell are held firmly together by the interlocking of their edges, without the use of nails, screws or similar fastening means between the shell and filler.

The firmness of the working portion of the board is attained by securing the underneath surface of the shell to the adjacent surface of the wooden filler by the use of a suitable adhesive substance; and, as will be brought out clearly hereinafter, the construction of the wooden filler is such as will permit it to yield in the vicinity of its outer edge where it has connection with the edge of the shell, thereby relieving the shell of excessive strain and at the same time placing the parts under a slight tension in order to hold them securely against relative movement.

In the accompanying drawing, wherein similar reference characters designate corresponding parts in the different views, Figure 1 represents a top plan of the board with a portion of the shell and filler broken away to show its construction; Fig. 2 is a bottom plan view of the board; Fig. 3 is a longitudinal section thereof; and Fig. 4 is an enlarged section through the edge of the board showing, in exaggerated proportions, the enamel coating of the shell and the thickness of the layer of adhesive substance.

1 represents a metallic shell which is rec-

tangular in shape and has rounded corners and a peripheral bead 2 that projects slightly above the body portion of the plate, or that portion which will be referred to herein-after as the working surface of the board 60 and upon which the dough is kneaded, in the event of its being used as a dough board. A flange 3 depends from the outer edge of the bead 2, and the lower edge of the flange is turned inwardly to form a lip 4. To protect 65 the metal against rust and deteriorating elements, and in order that the board may present an attractive appearance, and be very easily kept clean, I cover the metal shell with a heavy coating of enamel (shown in Fig. 4, 70 at 1^a). Because of the nature of the enamel, it leaves the surface of the lip 4 of the shell slightly uneven, when it hardens. This results from the enamel, when in its liquid state, draining to this portion of the shell 75 before it is baked.

The filler comprises a body portion 5, preferably of boards, which is secured by any suitable adhesive 6, such as glue, (represented by the heavy black line in Figs. 3 80 and 4) to the underneath surface of the working portion of the shell, and the outer edges of the body portion 5 are spaced inwardly some distance from the plane of the inner edge of the lip 4. To the underneath 85 surface of the portion 5, adjacent its edges, is secured the transverse and longitudinal members 7 and 8, respectively, the screws 9 being used for the purpose of holding the parts together, which screws have their tapered heads countersunk so as not to project beyond the underneath surface of said members. The outer corners of the ends of the members 7 are rounded to correspond to the shape of the corners of the shell, and the 95 outer edges of both the members 7 and 8 are rabbeted, as shown at 10.

In assembling the structure, after the body portion 5 has been secured in place by the adhesive substance 6, the members 7 and 8 100 are placed in position, in respective order, with their rabbeted edges engaging the lip 4 of the shell. It may be stated at this time that the thickness of the members 7 and 8 above the plane of the horizontal surface of 105 their rabbets 10 is somewhat greater than the distance between the planes of the underneath surface of the portion 5 and the upper surface of the lip 4. Because of these proportions, in assembling the board, the outer 110

edges of the members 7 and 8 are placed over the lip 4 and the members are then pressed against the body portion 5, in which position they are firmly held, under a slight tension, 5 by the screws 9, the outer portions of the members 7 and 8 yielding as a result of the proportions of the parts just described. It will be understood, also, that the members 7 and 8 yield to compensate for the uneven- 10 ness of the enamel.

It will be observed that the vertical dimension of the rabbet 10 is sufficient to elevate the lip 4 above and out of contact with a supporting surface upon which the board 15 may be placed, in order that the enamel of the shell may be protected against fracture from coming in contact with such supporting surface.

Having thus described my invention, what 20 I claim is:

1. An article of the character set forth comprising an enameled metallic shell having a substantially flat portion from the edge of which depends a flange that has, at its 25 lower edge, an inwardly directed lip, a filler for said shell that consists of a flat body that is secured to the underneath surface of the flat portion of the shell by an adhesive substance, and yielding members carried by 30 the filler and engaging the aforesaid lip.

2. An article of the character set forth comprising an enameled metallic shell having a substantially flat portion which is surrounded by a depending flange that terminates at its lower edge in an inwardly directed lip, and a filler for said shell that consists of a flat body portion that is secured to the underneath surface of the flat portion of the shell by an adhesive substance, 35 and yielding members carried by the body portion of the filler for engaging the lip of the shell and securing the parts against relative movement.

3. An article of the character set forth comprising an enameled metallic shell having a substantially flat portion from the edge of which depends a flange that has, at its lower edge, an inwardly directed lip, a filler for said shell that consists of a flat 45 body that bears against the underneath surface of the flat portion of the shell, and yielding members carried by the filler for engaging the aforesaid lip, the yielding members having portions that project below 50 the bottom plane of the lip.

4. An article of the character set forth comprising an enameled metallic shell having a substantially flat portion from the edge of which depends a flange that has, at its 55 lower edge, an inwardly directed lip, a

filler for said shell that consists of a flat body that is secured to the underneath surface of the flat portion of the shell by an adhesive substance, and yielding members carried by the filler for engaging the aforesaid lip, the yielding members having portions that project below the bottom plane of the lip.

5. An article of the character set forth comprising a metallic shell having a substantially flat working portion from the outer edge whereof depends a flange that terminates at its lower edge in an inwardly directed lip, and a filler for said shell which has a portion that engages the underneath 75 surface of the working portion of the shell, the edges of said portion of the filler being spaced from the depending flange of the shell a distance greater than the width of the aforesaid lip, the filler also having yielding extensions which project beyond its aforesaid engaging portion and overlie the lip of the shell.

6. An article of the character set forth comprising an enameled metallic shell having a substantially flat portion that is surrounded by a depending flange that terminates at its lower edge in an inwardly directed lip, and a filler for the shell which comprises a flat body portion of a thickness 90 less than the distance between the planes of the underneath surface of the shell and the opposed side of the lip, and yielding members that are secured to the underneath surface of the body portion and filler near its 95 edges, said members having their outer edges rabbeted to receive the lip of the shell, the thickness of said members above the rabbet being greater than the distance between the planes of the opposed surfaces of the lip 100 and the body portion of the filler, said members also having portions that project below the bottom plane of the lip.

7. An article of the character set forth comprising a metallic shell having a substantially flat portion from the edge of which depends a flange that has, at its lower edge, an inwardly directed lip, a filler for said shell that consists of a flat body that bears against the underneath surface of the flat portion of the shell, and yielding members carried by the filler for engaging the aforesaid lip.

In testimony whereof, I hereunto affix my signature in the presence of two witnesses.

LEE S. CHADWICK.
